UNITED STATES PATENT OFFICE.

HUGH GEMIGNANI, OF PITTSBURGH, PENNSYLVANIA.

STEAMING DEVICE.

1,124,884.

Specification of Letters Patent. Patented Jan. 12, 1915.

Application filed January 22, 1913. Serial No. 743,505.

To all whom it may concern:

Be it known that I, HUGH GEMIGNANI, a citizen of the United States of America, residing at Pittsburgh, in the county of Allegheny and State of Pennsylvania, have invented certain new and useful Improvements in Steaming Devices, of which the following is a specification, reference being had therein to the accompanying drawing.

10 This invention relates to a pressing device, and the primary object of my invention is the provision of positive and reliable means, as hereinafter set forth, for pressing velvet.

15 A further object of this invention is to provide a steaming device for velvet wherein the textile is moistened without fear of staining same during the operation, it being a well known fact that velvet textile 20 will stain if any water comes in contact therewith during the pressing operation and this device embodies a novel steam heat 25 pressing device to which is connected a brush having a steam exhaust, the brush and steam exhaust coöoperating with the device for pressing velvet garments.

With the above and other objects in view, the invention resides in a novel construction, combination and arrangement of parts to 30 be hereinafter specifically described and then claimed.

Reference will now be had to the drawing, wherein there is illustrated the apparatus partly in elevation, partly in perspective, 35 and partly in longitudinal section.

Further describing my invention in detail with reference to the drawing wherein like numerals denote corresponding parts throughout:—1 denotes a steam generating receptacle having a water gage 2 that permits of the quantity of water within the receptacle being easily determined. The receptacle 1 has a lid or closure 3, which is provided with a filling opening 4, said filling opening being normally closed by a spring held cap 5 that serves functionally as a safety valve.

7 denotes a spout carried by the lid 3 and provided with a conventional form of valve 50 8 having a nipple 9. Detachably mounted on the nipple 9 is the end of a hose 10 or other flexible connection, said hose having the opposite end thereof detachably connected to a valve 11, carried by the inlet pipe 12 of a sleeve shaped hollow and flat metallic holder or pressing board 13. The

holder 13 is preferably made of metal and of two sections with the edges of said sections interlocked or connected, as at 14. The inlet pipe 12 is located at one end of the 60 holder and the opposite end thereof is provided with an outlet pipe 15, which has a valve 16 connected to a hose 17 or other flexible connection.

18 denotes a brush body having bristles 19 and a curved handle 20. Extending longitudinally of the handle 20 and the body 18 is a tube 21, which is connected to the hose 17. The tube 21 at the outer end of the brush body 18 is provided with a needle 70 valve body 22 having a drain plug 23 and a goose neck 24. The goose neck 24 has a regulator 25 for controlling the exhaust of steam from the valve body 22.

By placing the receptacle 1 upon a stove, 75 burner or other heating medium, the water within the receptacle can be brought to a boiling point whereby steam will be generated. By disconnecting the hose 10 and 17 relatively to the holder 13, said holder 80 can be placed in the sleeve of a garment. By then attaching the hose 10 and 17 to the holder, the valve 11 can be opened to admit steam to the holder, whereby the sleeve upon the holder will be subjected to 85 the action of the steam.

To operate the pressing device, the velvet to be pressed is placed upon the pressing board, then the brush is applied over the velvet and the steam is permitted to run out 90 of the needle valve, the brush is kept moving all the time thus the velvet is moistened by the steam, smoothed by the brush and dried by the pressing board.

It is a well known fact that if any water 95 should fall upon velvet it would produce a stain which could not be removed and to overcome such objection, the needle valve is employed to discharge the steam, and a reservoir positioned behind the valve to collect all the water formed in the pipe, due to the condensation of steam, whereby as the steam is supplied to the velvet as the brush moves thereover, there is no possibility of the velvet becoming stained by the 100 water.

What I claim is:—

A device for pressing velvet fabric comprising a brush operable on the fabric, a steam spraying element carried by the 110 brush for spraying live steam upon the fabric during the operation of the brush,

means for establishing communication between said spraying element and a steam supply, and said spraying element further including means to collect the water condensate during the operation of the brush to prevent the condensate dropping upon the fabric when pressing the same.

In testimony whereof I affix my signature in the presence of two witnesses.

HUGH GEMIGNANI.
